UNITED STATES PATENT OFFICE.

WILLIAM J. L'ENGLE, OF NEW ORLEANS, LOUISIANA.

TURPENTINE-CUP.

1,017,679.

Specification of Letters Patent.

Patented Feb. 20, 1912.

Application filed August 1, 1910. Serial No. 574,924.

To all whom it may concern:

Be it known that I, WILLIAM J. L'ENGLE, a citizen of the United States, residing at New Orleans, in the parish of Orleans and 5 State of Louisiana, have invented certain new and useful Improvements in Turpentine-Cups, of which the following is a specification.

The object of my invention is to provide a 10 wire mesh cup designed to receive and sustain the water and gum proof paper cup, thus reducing the cost of maintaining cups for the gathering of crude gum turpentine.

As compared with the clay and sheet 15 metal cups in use, such a design as is contemplated by my invention is very much less expensive.

In the drawing, Figure 1 is a detail view 20 of a tree with my improved cup in position; Fig. 2 is a perspective view of the wire mesh cup; Fig. 3 is a transverse sectional view of the wire cup; Fig. 4 is a perspective view of the paper cup; Fig. 5 is a plan view of the blank from which the paper cup is 25 made, and Fig. 6 is a top plan view of the paper cup, one end of which is folded in position, while the other end is in partly unfolded position.

In the drawing, 1 represents a turpentine 30 cup holder constructed of wire mesh material. This holder is made from one piece of wire mesh shaped by dies, drawing, or folding to conform to the desired shape to fit the cup it is designed to hold and sustain. 35 The cup may be oblong or round or any other desired shape with one wall thereof concaved to conform to the perimeter of the tree. This wire mesh cup is provided with rebent upper edges to form a reinforcing 40 strip 2 as clearly shown in Fig. 3.

The paper turpentine cup 3 is formed 45 from one piece of suitable water and gum proof paper which is folded on the lines 4, 4, for the side members of the cup and 5, 5, for the end members of the cup, the folds 50 6, 7 and 8 forming flaps which are bent on the outside of the ends of the cup, thereby 55 securely holding the side members and the ends of the cup firmly into position. This construction produces a paper cup without 60 seams from one piece of paper. The paper cup is designed to fit snugly within the wire mesh cup; the wire mesh cup sustaining and supporting the paper cup against distortion. 65 As is usual, a suitable apron 9 is secured 70 to the tree and the wire mesh cup is sup-

ported under said apron by means of the usual peg or nail 10, the said cup being held up against the under face of the apron. The paper cup is then placed in the wire 60 mesh cup to receive the crude gum turpentine as it flows from the tree.

The water proof paper cup is placed in the wire mesh cup or receptacle at the beginning of the season. The paper cup 65 usually fills in about three weeks' time and as soon as filled, it, with its wire mesh holder or cup, is taken off the tree and the crude gum turpentine with the paper cup is thrown into the "dip" barrel, while the 70 wire cup or holder is replaced against the tree and a fresh paper cup inserted ready for the next dipping and this paper cup in turn when filled is tossed with the gum in it into the dip barrel, while the wire frame 75 is again placed in position on the tree and a new paper cup inserted in it. The dip barrel referred to is the usual receptacle set among the trees for the purpose of having emptied into it the contents of cups in the 80 immediate vicinity. The paper cups are removed from the crude gum turpentine in the course of refining or distilling.

Clay cups such as are universally used are 85 a source of considerable loss by reason of the fact that they are readily broken by ice forming in them, which not only results in the loss of the cup, but in the loss of the crude gum turpentine. These objections are entirely overcome by the use of my invention which will result in a very material 90 saving in this line of business. I believe that I am the first to use the basket-like holder with a water and gum proof paper removable lining, which lining constitutes 95 a cup. This combination results in simplicity, ease of handling, maximum capacity and minimum cost in the art of gathering crude gum turpentine.

The basket or cup 1 may be made of bamboo, willow, or any other material of which baskets are usually made.

I claim:—

1. In a device for gathering turpentine, the combination with a flexible liquid proof 105 turpentine cup, of a rigid support adapted to be secured to a tree and sustain the sides, ends and bottom of said cup throughout their entire area against bulging under the pressure and weight of the turpentine 110 therein.

2. In a device for gathering turpentine,

the combination with a flexible liquid proof turpentine cup comprising a single piece of paper, the sides of which are bent upward, the fullness at the ends being disposed in 5 overlapping folds with upwardly extended edges, whereby leakage is prevented, of a stiff holder adapted to be secured to a tree and constructed to receive said flexible cup and sustain its ends, sides and bottom

against bulging under the pressure and 10 weight of the turpentine therein.

The foregoing specification signed at New Orleans, this seventeenth day of July, 1910.

WILLIAM J. L'ENGLE.

In presence of two witnesses—

FRONIE BALLINTINE,
LINA LE BAS.
